UNITED STATES PATENT OFFICE.

CHARLES E. McMANUS, OF NEW YORK, N. Y.

MACHINE FOR ASSEMBLING BOTTLE CAPS.

Application filed May 28, 1921. Serial No. 473,429.

To all whom it may concern:

Be it known that I, CHARLES E. McMANUS, a citizen of the United States, residing at the borough of Manhattan, in the city, 5 county, and State of New York, have invented certain new and useful Improvements in Machines for Assembling Bottle Caps, of which the following is a specification, reference being had therein to the accompanying drawings, which form a part thereof.

My invention relates to machines for assembling bottle caps, and more particularly to a machine which will cement an untreated 15 cork or other similar, resilient disk, to a skirted or cupped metallic shell, and apply a finishing coating to only the exposed surface of the disk.

In the bottle cap art it has long been the 20 practice to cement disks of natural, or bonded granular, cork in metallic cupped shells having either a plain or fluted skirt. The cementing medium has either been applied directly between the disk and the metal 25 portion of the shell or to a paper collet treated on both sides with the cementing medium. Various cements have been used, the character of the cement always having been of a nature so that when heat is applied to the cap simultaneously with the application of pressure upon the disk, a firm 30 bond between the disk and the shell will occur when the critical temperature of the particular cement is such as to make it adhesive. It was necessary thereafter, to cool 35 the assembled shell, it being immaterial whether this cooling is done while the cap is subjected to pressure or when it is free therefrom. It is old in this art to use a 40 variety of different cements. Some manufacturers use resinous cements, others casein compounds, and still others albuminous compound, it being necessary to compound with the base of the cement, ingredients to facilitate 45 the rapid drying or setting thereof, while permitting them to remain fluid until applied to the metallic shell. In some instances the sheet tin from which the shells are formed are "spotted" with the cement, 50 viscosity of the cement being neither essential nor desirable.

Albuminous and casein cements have been used for many years in the production of corks for champagne bottles, and in my 55 present application I lay no claim to the use of any particular cement, since the matter

of the adhesive employed is merely one of selection.

The caps assembled in the machine of my invention do not require the employment of 60 an adhesive coated collet, which has heretofore been used primarily because of the likelihood of the porosity of different disks, and the desirability of interposing a gas impervious sheet between same and the top of 65 the shell so as to avoid the possible entrance of gases from a bottle between the disk and the shell with a resultant development of what is known in the trade as "leakers". A paper collet might be used, however, but 70 no advantageous results are secured thereby. This result flows from the application of the surface finish to the disk.

In order to dispense with the collet, it has been the general practice in this art to apply 75 to all surfaces of the cork disk, a coating of paraffin, which is highly objectionable, in that it interferes with an effective bonding of the disk to the shell, or requires a special ingredient in the adhesive. 80

With the above conditions in mind, I have produced an automatic machine so constructed that the adhesive or cement will be applied to the top of the shell, a cork disk will be thereafter delivered to the shell, and 85 a finishing wax composition will be applied to only the exposed surface of the cork, the completely assembled cap thereafter being delivered to a finishing head, wherein it will be simultaneously subjected to heat and 90 pressure for the purpose of developing a critical temperature in the cement or adhesive and secure a proper bond between the disk and the shell while at the same time spreading the finishing composition and 95 forcing it into any interstices in the disk.

The machine has large capacity determined by the duration of the treatment of the completely assembled cap in the finishing head, the caps being delivered from said 100 head and cooled in the air while undergoing inspection by the machine operator.

The means for applying the cement or adhesive, and for applying the finishing compound, are so constructed as to limit the 105 quantity of material delivered by each, while avoiding possible clogging of the mechanism. The construction of these mechanisms also prevents the delivering of the material thereby except when an assembled cap is in 110 the proper position in relation thereto, thus avoiding fouling of the machine.

The mechanisms for intermittently feeding the shells and delivering said shells from a hopper in proper position with relation to said feeding mechanism, and the detailed 5 construction of the finishing head are all old and well known in the art and immaterial to the invention, which resides more particularly in combining with mechanisms capable of these functions, irrespective of their 10 detailed construction, adhesive and finishing compound applying means in a definite relation to these mechanisms and to each other, for the purpose of securing a certain, and completely finished product.

15 The invention consists primarily in a machine for assembling bottlecaps, embodying therein means for feeding metallic shells, having therein an adhesive or cement responsive to heat, means delivering a cushion disk within said shell and upon the cement 20 therein contained, means adapted thereafter to apply a wax composition to the exposed surface of said disk, and means adapted to apply heat and pressure to said disk 25 and said shell after said wax composition has been applied thereto, and in such other novel features of construction and combination of parts as are hereinafter set forth and described, and more particularly 30 pointed out in the claims hereto appended.

Referring to the drawings,

Fig. 1 is a side elevation broken away and condensed, of a machine embodying my invention, showing a portion only of the finishing head and omitting the details of the shell feeding mechanism;

Fig. 2 is a similar, plan view of the machine, omitting the hopper and its delivery chute, and a portion of the finishing head;

40 Fig. 3 is an enlarged, cross sectional detail view of the cement adhesive dropper; and

Fig. 4 is a similar view of the wax dropper.

45 Like letters refer to like parts throughout the several views.

The embodiment of my invention shown in the drawings is illustrated in connection with an old and well known type of bottle 50 cap assembling machine embodying therein oppositely disposed runways 10, adapted to receive the fluted edge of the skirt and the shell, the upper portion of the shell depending between these runways, where it 55 may be engaged by the usual intermittently actuated feed bar 11.

At one end of said tracks is a rotary table 12 upon which the caps are delivered with the skirt presented upwardly, from an ordinary 60 cap feeding mechanism not shown in the drawings but old and well known in the art. At the other end of said tracks is a finishing head 13 of the usual and well known construction, having thereon a sequence of spring-pressed plungers 14 adapt-

ed to develop and maintain pressure upon the completed cap through the disk preparatory to the delivery of the cap for cooling purposes. Said head is maintained at the desired temperature by a heating device 15, preferably a burner extending under the various plungers 14 to adjacent the delivery point for the caps.

Each of the plungers 14 is adapted to be engaged by a fixed cam 16 adjacent the delivery point for the caps with the two fold object of permitting the ejection of a completely assembled cap and its delivery to a cooling and inspection belt 17, said cam terminating at the end of the tracks 10 so that with the actuation of said finishing head 13 after the delivery of each cap thereto, the plunger will automatically descend and remain in the lowered position until it reaches the cam 16, at which point the cement will have been brought to the desired critical temperature, be properly diffused about the surfaces of the cap and the disk, and be in condition to permit the final setting of the adhesive or cement by the removal of the cap from the high temperature zone, and its exposure to atmospheric air about the delivery belt.

Intermediate the delivery disk 12 and the finishing head 13 is a cork disk feeding 95 mechanism also of old and well known construction, consisting of a tube 18 in which disks are adapted to be automatically stacked by a mechanism not shown, and a reciprocatory plunger 19 adapted to push 100 the lowermost disk from below said tubes and to a position below a reciprocatory plunger 20 carried by a vertically movable slide 21 mounted in suitable slideways.

The slide 19 is actuated by means of a 105 rocking lever 22 actuated from a cam 23, which cam also actuates the slide 21. Said cam is carried by a shaft 24 which also applies power to all other mechanisms in the machine insofar as the assembling of the cap is concerned, as distinguished from the detailed mechanisms of the shell and disk feeding attachments.

The mechanisms heretofore described are those embodied in one type of assembling 115 machine which has been used for some years past, and is shown and described merely as exemplifying one type of machine with which my invention has been successfully used, it being understood, however, that the details of this mechanism are immaterial to the invention, which may be readily adapted to machines having an entirely different mechanism for advancing the shells in relation to the various other mechanisms of 125 the machine, for delivering the shells to this mechanism, for delivering disks to the shells and for applying pressure to and subjecting the shells to heat while in the finishing head. The invention contemplates 130

merely some means for feeding the shells in proper position, some means for advancing them so as to successively subject them to other mechanisms of the machine, some 5 means for placing the cork disks in the shell under certain conditions with relation to other mechanisms, and some means for applying heat and pressure to the assembled cap before cooling same, combined with 10 means for supplying a suitable adhesive or cement to the shell before delivering the cushion disk thereto and for applying a finishing compound to the disk after the cork has been so delivered but before the 15 completely assembled cap is subjected to heat and pressure.

Intermediate the disk 12 and the plunger 20 is a vertical slide 25 actuated by means of the cam 26 carried by the shaft 24, and 20 the connecting rod 27 co-operating with said cam by means of the usual strap 28. Carried by said slide is a cylinder 29 having mounted therein a piston 30 carrying an upwardly extended funnel-mouthed tube 31, 25 the lower edge of which engages a stop 32 within the piston. Acting against said piston is a spring 33 encircling the tube 31 and acting between the stop 32 and the piston 30, thus being in a position where the 30 adhesive will not contact therewith and avoiding possibility of retardation of the actuation of the piston, which is undesirable particularly in high speed machines, as a result of the fouling of the spring.

35 The tube 31 communicates with the cylinder 29 through ports 34 arranged between the piston 30 and the lower end of said cylinder, the bottom of the opening in the tube 31 being closed so as to limit the communication between said tube and the piston to said ports 34.

The lower end of the cylinder is provided 40 with a bevelled valve seat 35 about the outlet of the cylinder and adapted to co-operate with a cone shaped valve block 36 carried by the piston 30.

Below the valve block 36 is a hollow stem 37 having ports 38 normally positioned below the valve seat 35 but sufficiently closely 45 thereto to place the hollow stem 37 in communication with the cylinder through said openings 38 when the piston is raised in a manner which will be hereinafter referred to, but to close said ports 38 when the valve 55 is closed.

Below and about the discharge end of the stem 37 is a pad 39 having a flared opening therein, in register with the opening in the stem 37, for directing the adhesive upon the 50 inner top of the shell or causing the spotting of the shell for a considerable area about its axis. The pad 39 will also, in the course of use, gradually have accumulated on the surface thereof, a coating of the adhesive used, 55 which will serve to prevent the delivery of

an excess quantity of the adhesive or cement and ultimately secure a wider diffusion thereof upon the inner top of the shell.

Since a constant agitation of the adhesive or cement is undesirable, I provide means 70 whereby said adhesive or cement will be delivered within the tube 31 with a substantially uniform slow rate of flow, as by a sequence of drops. To secure this result, I use a dropper consisting of an immovable 75 reservoir 40 having attached thereto an old and well known type of dropper nozzle 41 which will permit the adhesive to flow by a sequence of timed drops from the reservoir through the dropper nozzle mechanism 41 80 into the funnel top of the tube 31.

The dropper attachment associated with the reservoir 40—42 is provided with the usual adjustment means for determining the volume of the drops and the frequency 85 thereof and a removable closure plug for filling purposes.

The adhesive or cement used is preferably such as will not require heating in the reservoir, although by providing a suitable dropping mechanism, a fusible, resinous or other gum cement might be used, although adhesive or cement having a casein, serum albumen or egg albumen base may also be used and are in fact preferable.

If desired, the ordinary collet delivery mechanism may be substituted for that heretofore described, although I have found in actual practice that the use of this collet is unnecessary with a cap assembled in a machine embodying my present invention.

Intermediate the plunger 20 and the finishing head 13 and closely adjacent the latter so as to be within the high temperature zone of the machine, is a reservoir 42 105 having a dropping attachment 43 of any desired old and well known construction, which reservoir is adapted to deliver a wax composition, preferably having a base of cerasine wax, to the tubular funnel-mounted 110 extension 44 of a piston 45 mounted in a cylinder 46 supported by the bracket 47 from the slide 20. The cylinder 46 is provided with a stop ring 48, a spring 49 acting between said stop ring and the piston 45. 115 The bottom end wall of the cylinder is provided with a bevelled seat 50 and the lower face of said piston is provided with a cone valve 51 co-operating therewith. The tubular member 44 has ports therein adjacent 120 and below the piston 45 while the valve 51 is provided with a depending stem 52.

It will be observed that the outlet ports through the bottom of the cylinders 29 and 46 are normally closed, but that with the descent of these cylinders and the engagement of the pad 39 and the stem 52 with a cap positioned directly beneath said cylinders respectively and in axial alinement therewith, said ports will be opened, thus 130

permitting the cement or adhesive to pass from the cylinder 29 into the shell, and the wax surfacing composition to pass from the cylinder 46 upon the cork disk, while the cylinders are in their lowermost position, and cause a forcible ejection of some of said materials from the cylinders during a portion of the period during which said pistons are moving away from the shell.

10 The delivery belt 17 extends for substantially the entire length of the machine, terminating adjacent the table 12 at which point it is elevated and a transversely extending conveyer belt 53 is passed thereunder, the completed caps being directed upon said transverse belt by the laterally pitched transfer plate 54. Extending parallel with the belt 17, and below the belt 53, is a wide conveyer belt 55 to which the completed caps pass in groups along a slide 56, instead of one at a time as in their progress with the belts 17 and 53, said caps being removed from the belt 53 and delivered to said slide by a rotary wiper 57 so timed in its movements as to remove the caps from the belt 53 when a predetermined number of caps are on the belt 53 in the path of the wiper.

The operation of the herein described machine is substantially as follows:—

30 With each cycle of the machine a metallic cap is transferred from the table 12 to the runway between the tracks 10 and is advanced with a step by step movement, or intermittently, by the rack 11 until it reaches 35 the finishing head 13. During the dwell between succeeding feeding movements of said rack, an adhesive or cement will be applied to one shell, a cork disk will be fed to another shell intermediate said first named shell and the finishing head, and the wax 40 finishing compound will be applied to the cork disk in a third shell intermediate the point of delivery of the disk to the shell and the finishing head. During this interval the 45 finishing head will be rotated one step or the distance between succeeding plungers 14 thereon, and a completely finished cap, with the exception of the cooling thereof, will be delivered by said delivery head to the delivery and inspection belt 17, another cap will be delivered to the transverse conveyer belt 53 by the transfer plate 54, and when a sufficient number of caps are upon said last 50 named belt, they will be wiped therefrom so as to pass over the slide 56 to the wide conveyer belt 55 by which they will be delivered to the packing case, or a counting machine, as desired. The completed caps may be inspected when upon the belt 17 or upon the 55 belt 55, as desired, imperfect caps being removed by the operator.

The length of the belt 17 will afford ample time for the caps to cool, which cooling is necessary to cause the adhesive or cement to 60 set sufficiently firmly to form the necessary

intimate and lasting bond between the metal of the cap and the inner face of the disk, which may be formed either of natural cork, or of what is known in the trade as, "composition cork".

70 Since the functionings of the machine as to any cap are sequential, a detailed description of its operation in relation to a single cap will be given, it being understood, however, that notwithstanding the time element 75 between the delivery of the shell from the table 12 to its delivery upon the transverse belt 53, one cap will be completed and delivered with each cycle of the machine or each rotation of the shaft 24.

80 It will also be noted that the slides 19, 21 and 25 are all actuated substantially simultaneously, although the cams actuating same may be so set as to give them a slight lead as compared with the rack bar feeding movement, although this is unnecessary, since there will be a sufficient dwell between feeding actuations of said rack bar to permit the adhesive or cement, and the cork disk to be properly applied to the shell and the wax 90 finishing compound to be properly applied to the exposed face of the disk.

85 As a shell progresses along the tracks or ways 10, and comes to rest in axial alinement with and directly under the cylinder 29, 95 this cylinder will descend and bring the pad 39 into engagement with the inner top of the shell so that the continued descent of said cylinder will cause the piston to remain stationary, thus unseating the valve block 36 100 and opening the ports 38 so as to place the interior of the cylinder in communication with the bore of the stem 37. At the same time the sub-atmospheric pressure thus developed within the cylinder will draw the fluid adhesive or cement from within the tube 31 to below the piston, this cement flowing by gravity through the ports 38, stem 37 and pad 39 onto the central portion of the shell. The rounded top of the shell will expose a considerable area thereof below the said pad so that with the reversal of movement of the cylinder, the pressure developed within the lower part of the cylinder will be vented in part through the open top of the 110 tube 31 and in part through the stem 29, thus tending to procure a greater diffusion of the adhesive or cement about the shell.

115 Prior to the next actuation of the rack bar 11, the cylinder 29 will be elevated so as 120 to permit the spring 33 to move the piston to its lowermost position while positioning the pad out of the path of movement of the shell.

125 As the shell with the contained cement progresses toward, and finally comes to rest under, the plunger 20, the slide 19 is actuated to move a disk from below the tube 18 and deposit it within the stationary shell upon the adhesive or cement.

After receiving the cork or cork composition disk, the shell will be brought directly beneath the cylinder 46 which, as the cap comes to rest, will descend and have the same mode of operation as the cylinder 29 and its appurtenances, in delivering a cerasine wax composition upon the exposed surface of the disk, the valve arrangement shown causing a somewhat greater diffusion of this composition than is secured by the construction used in connection with the cylinder 29.

Thereafter the assembled structure with its superficial coating of wax composition will be conveyed to the finishing head, and with the next actuation of said head, pressure will be applied thereby as the plunger 14 directly above the cap passes from the control of the cam 16, the temperature of the assembled cap while under pressure being raised by the heater 15 while it is progressing about the finishing head.

The subjecting of the assembled cap to heat will have the effect of causing a uniform wax film to be formed upon the exposed surface of the cork or cork composition disk, except in the event of small voids in said surface which will be filled by the wax, thus giving a smooth uniform surface to the disk and closing any pores through which gas from the charged liquid contents of a bottle can pass to between the disk and the inner top of the shell.

At the same time, the application of heat and pressure will have the effect of causing the desired intimate relation between the inner top of the shell and the adjacent surface of the disk, so that when the critical temperature of the cement or adhesive is reached, these parts will be closely associated, thus not only securing a thorough diffusion of the cement or adhesive, but assuring the desired intimacy in the bond secured thereby. This practice is old and well known in the arts, it being necessary to the securing of a proper joinder of any materials by means of a cement or adhesive.

As the completely assembled cap leaves the finishing head, and is removed therefrom and deposited upon the belt 17, the cement will be incompletely set, although a subsequent exposure to atmospheric air will permit its cooling to a point where it will be set, becoming sufficiently hardened to make the separation of the disk from the shell practically impossible without mutilation of the former.

Since with the selection of a suitable adhesive or cement the time required to complete a cap in the finishing head will be between ten and twelve seconds, it will be appreciated that the machine of my invention may be operated at high speeds.

While the machine is in operation, the adhesive or cement and also the wax composi-

tion will flow continuously from the reservoirs 40 and 42 respectively, falling drop by drop into the funnel-shaped top of the tubes 31 and 44, each drop being divided by the mechanism associated with said tubes to secure the proper quantity of the adhesive or cement and of the wax composition in each shell or upon each disk.

The fixed relation of the said reservoirs not only prevents undesirable agitation of the fluid therein contained, but will permit the convenient refilling of these reservoirs from time to time, and thus avoid the necessity for the storage of an excessive volume of these materials which might result in their deterioration or difficulty in securing a proper flow thereof for the purposes of the machine.

I would not be understood as intimating that viscosity is essential to the adhesive or cement after it is applied to the shell, it being possible to spot the tin sheets from which shells are formed, with this cement, and permit it to stand for a reasonable length of time, the coating thereof being so thin that it will not interfere with the operation of the punch presses in forming the shells from the sheets. The application of heat to practically all cements of the nature herein referred to, whether fusible or non-fusible, causes reactions which at a certain critical temperature will make them adhesive.

Of course if the adhesive be applied to the shell before it is delivered to the machine, the reservoir 40 and its appurtenances are not required, but since in handling sheets it is possible that oil or other foreign substances may come in contact with the surface of the adhesive, for ordinary purposes it is preferable to apply the adhesive to the finished cap in the manner herein described.

The use of the wax finishing compound is particularly desirable when the caps contain composition cork disks, although it may be advantageous to be used with natural cork disks.

It is not my intention to limit the invention to the detailed mechanisms about the machine apart from that arrangement or combination of parts by which the wax compound is applied to one surface of the disk before subjecting the assembled shell and disk to pressure so as to secure the proper diffusion, and penetration of the wax, and proper reaction of other ingredients in the compound, to secure gas and liquid impermeability about interspaces of the disk and impart a better finish thereto.

Having described the invention, what I claim as new and desire to have protected by Letters Patent is:—

1. A machine for assembling bottle caps, embodying therein means for feeding metallic shells, having therein an adhesive or

- ment responsive to heat, means delivering a cushion disk within said shell and upon the cement therein contained, means adapted thereafter to apply a wax composition to the exposed surface of said disk, and means adapted to apply heat and pressure to said disk and said shell after said wax composition has been applied thereto.
2. A machine for assembling bottle caps, embodying therein means for feeding metallic shells, having therein an adhesive or cement responsive to heat, means delivering a cushion disk within said shell and upon the cement therein contained, means adapted thereafter to apply a wax composition to the exposed surface of said disk, and means adapted to apply heat and pressure to said disk and said shell after said wax composition has been applied thereto.
3. A machine for assembling bottle caps, embodying therein means for feeding metallic shells, having therein an adhesive or cement responsive to heat, means delivering a cushion disk within said shell and upon the cement therein contained, a reciprocatory cylinder having a downwardly presented outlet port above the path of movement of the shell, a piston within said cylinder carrying a valve block co-operating with said outlet port, a spring acting to normally depress said piston and said block, a piston stem projecting through said port and beyond said cylinder whereby as said cylinder descends, said port will be automatically opened through the movement of said block caused by the engagement of said stem with the shell, means supplying a limited quantity of wax composition to said cylinder, means whereby said cylinder will be actuated when a shell is properly positioned thereunder, and means adapted to apply heat and pressure to said disk and said shell after said wax composition has been applied thereto.
4. A machine for assembling bottle caps, embodying therein means for feeding metallic shells, having therein an adhesive or cement responsive to heat, means delivering a cushion disk within said shell and upon the cement therein contained, a reciprocatory cylinder having a downwardly presented outlet port above the path of movement of the shell, a piston within said cylinder carrying a valve block co-operating with said outlet port, a spring acting to normally depress said piston and said block, a piston stem projecting through said port and beyond said cylinder whereby as said cylinder descends, said port will be automatically opened through the movement of said block caused by the engagement of said stem with the shell, means supplying a limited quantity of wax composition to said cylinder, means whereby said cylinder will be actuated when a shell is properly positioned thereunder.
5. A machine for assembling bottle caps, embodying therein means for feeding metallic shells, having therein an adhesive or cement responsive to heat, means delivering a cushion disk within said shell and upon the cement therein contained, a reciprocatory cylinder having a downwardly presented outlet port above the path of movement of the shell, a piston within said cylinder carrying a valve block co-operating with said outlet port, a spring acting to normally depress said piston and said block, a piston stem projecting through said port and beyond said cylinder whereby as said cylinder descends, said port will be automatically opened through the movement of said block caused by the engagement of said stem with the shell, a tube carried by said piston and having ports therein between the piston and the outlet port of said cylinder, said spring encircling said tube so as to be out of engagement with the fluid wax composition, an immovable reservoir, a dropper attachment carried thereby and adapted to deliver the composition therefrom to said tube, means whereby said cylinder will be actuated when a shell is properly positioned thereunder, and means adapted to apply heat and pressure to said disk and said shell after said wax composition has been applied thereto.
6. A machine for assembling bottle caps, embodying therein means for feeding metallic shells, a reservoir adapted to receive a fluid cement, a reciprocatory cylinder into which the cement from said reservoir passes in limited quantities and is delivered beneath said piston, a stem carried by said piston adapted to actuate same upon its engagement with a shell as said cylinder descends, means whereby the cement from said cylinder is delivered with the actuation of said piston into the shell, means whereby said cylinder will be reciprocated as a shell is properly positioned thereunder, means delivering a cushion disk within said shell and upon the cement therein contained, means adapted thereafter to apply a wax composition to the exposed surface of said disk, and means adapted to apply heat and pressure to said disk and said shell after said wax composition has been applied thereto.
7. A machine for assembling bottle caps, embodying therein means for feeding metallic shells, a reciprocatory cylinder, a piston within said cylinder, a tube carried by said piston and having ports therein between said piston and the bottom of the cylinder, a

- spring acting upon said piston and encircling said tube, whereby engagement of cement with said spring is prevented, a tubular stem having ports therein adapted to 5 communicate with said cylinder below said piston and being open at the bottom, said ports being normally closed by the lower end of the cylinder, said stem projecting below said cylinder whereby the ports there- 10 through will be automatically placed in communication with the cylinder by the engagement of said stem with the shell as the cylinder descends, means supplying a limited quantity of cement to said tube and there- 15 through to said cylinder, means delivering a cushion disk within said shell and upon the cement therein contained, means adapted thereafter to apply a wax composition to the exposed surface of said disk, and means 20 adapted to apply heat and pressure to said disk and said shell after said wax composition has been applied thereto.
8. A machine for assembling bottle caps, embodying therein means for feeding metallic shells, a reciprocatory cylinder, a piston 25 within said cylinder, a tube carried by said piston and having ports therein between said piston and the bottom of the cylinder, a spring acting upon said piston and encircling said tube, whereby engagement of cement with said spring is prevented, a tubular stem having ports therein adapted to 30 communicate with said cylinder below said piston and being open at the bottom, said ports being normally closed by the lower end of the cylinder, said stem projecting below said cylinder whereby the ports there- 35 through will be automatically placed in communication with the cylinder by the engagement of said stem with the shell as the cylinder descends, an enlarged pad carried by said tubular stem adjacent the outlet thereof, having a flaring opening there- 40 through in register with the opening in said tubular stem, a fixed reservoir, a dropping attachment carried thereby and adapted to deliver a limited quantity of cement to said tube, and therethrough to said cylinder, 45 means delivering a cushion disk within said shell and upon the cement therein contained, means adapted thereafter to apply a wax composition to the exposed surface of said disk, and means adapted to apply heat 50 and pressure to said disk and said shell after said wax composition has been applied thereto.
9. A machine for assembling bottle caps, embodying therein means for feeding metallic shells, a reciprocatory cylinder, a piston 55 within said cylinder, a tube carried by said piston and having ports therein between said piston and the bottom of the cylinder, a spring acting upon said piston and encircling said tube, whereby engagement of cement with said spring is prevented, a tubular stem having ports therein adapted to 60 communicate with said cylinder below said piston and being open at the bottom, said ports being normally closed by the lower end of the cylinder, said stem projecting below said cylinder whereby the ports there- 65 through will be automatically placed in communication with the cylinder by the engagement of said stem with the shell as the cylinder descends, an enlarged pad carried by said tubular stem adjacent the outlet thereof, having a flaring opening there- 70 through in register with the opening in said tubular stem, a fixed reservoir, a dropping attachment carried thereby and adapted to deliver a limited quantity of cement to said tube, and therethrough to said cylinder, 75 means delivering a cushion disk within said shell and upon the cement therein contained, means adapted thereafter to apply a wax composition to the exposed surface of said disk, and means adapted to apply heat 80 and pressure to said disk and said shell after said wax composition has been applied thereto.
10. A machine for assembling bottle caps, embodying therein means for feeding metallic shells, a reservoir adapted to receive a fluid cement, a reciprocatory cylinder into which the cement from said reservoir passes in limited quantities and is delivered beneath said piston, a stem carried by said piston adapted to actuate same upon its engagement with a shell as said cylinder descends, means whereby the cement from said cylinder is delivered with the actuation of said piston into the shell, means whereby 90 said cylinder will be reciprocated as a shell is properly positioned thereunder, means delivering a cushion disk within said shell and upon the cement therein contained, a reciprocatory cylinder having a downwardly presented outlet port above the path of movement of the shell, a piston within said cylinder carrying a valve block co-operating with said outlet port, a spring acting to normally depress said piston and said block, a piston stem projecting through said port and beyond said cylinder whereby as said cylinder descends, said port will be automatically opened through the movement of said block caused by the engagement of said stem with the shell, means supplying a limited quantity of wax composition to said cylinder, means whereby said cylinder will be actuated when a shell is properly positioned thereunder, and means adapted to 100 apply heat and pressure to said disk and said shell after said wax composition has been applied thereto.
11. A machine for assembling bottle caps, embodying therein means for feeding metallic shells, a reservoir adapted to receive a fluid cement, a reciprocatory cylinder into which the cement from said reservoir passes in limited quantities and is delivered beneath said piston, a stem carried by said piston 110

- adapted to actuate same upon its engagement with a shell as said cylinder descends, means whereby the cement from said cylinder is delivered with the actuation of said 5 piston into the shell, means whereby said cylinder will be reciprocated as a shell is properly positioned thereunder, means delivering a cushion disk within said shell and upon the cement therein contained, a reciprocating cylinder having a downwardly presented outlet port above the path of movement of the shell, a piston within said cylinder carrying a valve block co-operating with said outlet port, a spring 10 acting to normally depress said piston and said block, a piston stem projecting through said port and beyond said cylinder whereby as said cylinder descends, said port will be automatically opened 15 through the movement of said block caused by the engagement of said stem with the shell, means supplying a limited quantity of wax composition to said cylinder, means whereby said cylinder will be actuated when 20 a shell is properly positioned thereunder, and means adapted to apply heat and pressure to said disk and said shell after said wax composition has been applied thereto, said wax composition supplying means being located adjacent said last named means, whereby the wax composition will be within a high temperature zone.
12. A machine for assembling bottle caps, embodying therein means for feeding metallic shells, a reciprocating cylinder, a piston within said cylinder, a tube carried by said piston and having ports therein between said piston and the bottom of the cylinder, a spring acting upon said piston and encircling said tube, whereby engagement of cement with said spring is prevented, a tubular stem having ports therein adapted to communicate with said cylinder below said piston and being open at the bottom, said ports 40 being normally closed by the lower end of the cylinder, said stem projecting below said cylinder whereby the ports therethrough will be automatically placed in communication with the cylinder by the engagement of said 45 stem with the shell as the cylinder descends, an enlarged pad carried by said tubular stem adjacent the outlet thereof, having a flaring opening therethrough in register with the opening in said tubular stem, a fixed reservoir, a dropping attachment carried thereby and adapted to deliver limited 55 quantities of cement to said tube, and therethrough to said cylinder, means delivering a cushion disk within said shell and upon the cement therein contained, a reciprocating cylinder having a downwardly presented outlet port above the path of movement of the shell, a piston within said cylinder carrying a valve block co-operating with said outlet port, a spring acting to normally depress 60
- said piston and said block, a piston stem projecting through said port and beyond said cylinder whereby as said cylinder descends, said port will be automatically opened through the movement of said block caused by the engagement of said stem with the shell, a tube carried by said piston and having ports therein between the piston and the outlet port of said cylinder, said spring encircling said tube so as to be out of engagement with the fluid wax composition, an immovable reservoir, a dropper attachment carried thereby and adapted to deliver the composition therefrom to said tube, means whereby said cylinder will be actuated when a shell is properly positioned thereunder, and means adapted to apply heat and pressure to said disk and said shell after said wax composition has been applied thereto.
13. A machine for assembling bottle caps, embodying therein means for feeding metallic shells, having therein an adhesive or cement responsive to heat, means delivering a cushion disk within said shell and upon the cement therein contained, means adapted thereafter to apply a wax composition to the exposed surface of said disk, means adapted to apply heat and pressure to said disk and said shell after said wax composition has been applied thereto, and a conveyer system adapted to receive caps from said last named means and expose them to atmospheric air while conveying them therefrom, whereby the cement and the wax are set under lower temperatures than those prevailing adjacent said means.
14. A machine for assembling bottle caps, embodying therein means for feeding metallic shells, having therein an adhesive or cement responsive to heat, means delivering a cushion disk within said shell and upon the cement therein contained, means adapted thereafter to apply a wax composition to the exposed surface of said disk, means adapted to apply heat and pressure to said disk and said shell after said wax composition has been applied thereto, a long conveyer belt adapted to receive caps one at a time from said last named means, a short conveyer belt extending transversely of and below said first named belt, a wide conveyer belt below said transversely extending conveyer belt, extending at right angles thereto, a slide extending from adjacent one of said belts to adjacent the other, and a rotary wiper adapted to force a group of caps from said transverse belt upon said slide.
15. A machine for assembling bottle caps, embodying therein means for feeding metallic shells, means for applying a cement with in said shell, means delivering a cushion disk within said shell and upon the cement therein contained, means adapted thereafter to apply a wax composition to the exposed surface of said disk, means adapted to apply 125
- 130

heat and pressure to said disk and said shell after said wax composition has been applied thereto, and a conveyer system adapted to receive caps from said last named means and expose them to atmospheric air while conveying them therefrom, whereby the cement and the wax are set under lower temperatures than those prevailing adjacent said means.

10 16. A machine for assembling bottle caps, embodying therein means for feeding metallic shells, means for applying a cement within said shell, means delivering a cushion disk within said shell and upon the cement there-
15 in contained, means adapted thereafter to apply a wax composition to the exposed surface of said disk, means adapted to apply heat and pressure to said disk and said shell after said wax composition has been applied

thereto, a long conveyer belt adapted to receive caps one at a time from said last named means, a short conveyer belt extending transversely of and below said first named belt, a wide conveyer belt below said transversely extending conveyer belt, extending at right angles thereto, a slide extending from adjacent one of said belts to adjacent the other, and a rotary wiper adapted to force a group of caps from said transverse belt upon said slide.

In witness whereof I have hereunto affixed my signature, in the presence of two subscribing witnesses, this 3d day of May, 1921.

CHARLES E. McMANUS.
